UNITED STATES PATENT OFFICE.

MARTIN R. ETHRIDGE, OF LYNN, MASSACHUSETTS.

LASTING-MACHINE.

SPECIFICATION forming part of Letters Patent No. 269,841, dated January 2, 1883.

Application filed August 14, 1882. (No model.)

To all whom it may concern:

Be it known that I, MARTIN R. ETHRIDGE, of Lynn, in the county of Essex, of the State of Massachusetts, have invented a new and useful Improvement in Machinery for Lasting Boots or Shoes; and I do hereby declare the same to be described in the following specification and represented in the accompanying drawings, of which—

10 Figure 1 is a top view, Fig. 2 a side elevation, Fig. 3 a longitudinal section, and Fig. 4 a transverse section, of a machine embodying my invention. The remaining figures, 5, 6, 7, 8, and 9, are hereinafter described.

15 The invention consists in the details of construction hereinafter pointed out.

In the drawings, A denotes the frame of the machine, it being provided with two posts, B C, for the support of a last with an upper 20 upon it. Each of these posts slides vertically in a guide or standard, D, and rests upon a rotary circular-shaped cam, E, extending into the standard and underneath the lower end of the post, which rests on the circular or annular inclined portion of the cam. In Fig. 1 each cam E is partly represented in dotted lines. In Fig. 2 one cam is shown in elevation and in front of one standard, and with the foot of the post B resting on it, (the said cam,) and 25 the other cam is shown as in rear of its standard. Each cam is a disk inclined on its top in a circular path, it being pivoted at its center to the base of the standard, so as to be readily revoluble thereon by hand in order to raise 30 or lower the part resting on its annular incline. The base part a of each standard is slotted, as shown at b, to receive one or more clamp-screws, c, which go down through the slot and are screwed into the base d of the 35 frame. A top view of one of the standards, with its base and clamp-screw, is shown in Fig. 5. On revolving the cam the standard can be forced upward or lowered, as occasion 40 may require, and by means of the slot and clamp-screw of its base the standard may be adjusted either toward or away from the other standard, as may be required.

Pivoted to the frame A are two levers, F F, having their longer arms connected with a 45 pedal, G, in order that when the pedal is depressed by the foot of an attendant the short-

er arms of the levers may be caused to approach each other. Each lever has projecting from its upper arm an arched piece, H, which is grooved to receive a chain, I, which embraces the two arched pieces in their grooves and goes between two grooved guide-rollers, e e, and at its ends is fastened to the periphery of a wheel, f. The said wheel f is supported by a standard, g, and there is fixed to the wheel 60 a gear, h, that engages with the teeth of a sectoral lever, i, pivoted to the standards. This lever carries a stop-lever pawl, k, that works into the teeth of a stationary ratchet-wheel, l, fixed on the stationary fulcrum of the lever, 65 all being arranged as represented. On moving the lever in the right direction the wheel f may be revolved so as to cause the chain I to be wound upon it, and in consequence thereof to force inward the arched pieces H and 70 the upper arms of the levers F F, the pawl-lever and the stationary ratchet-wheel serving, as may be required, to hold the said levers from moving in contrary directions.

Fastened to each of the upper arms of the 75 levers F (such arm being T-shaped, as shown in Fig. 3) are three jaws, m n o, whose office is to turn the upper down upon the insole on the last. The two jaws m o are to be attached to the upper part of the arm by means which 80 will admit of their being adjusted to different distances from the intermediate jaw, n, as the size of the last may require, the said jaw n being permanently fixed to the lever F.

Secured upon the jaws m n o are adjustable 85 gages p, which determine the proper position of the outer sole to the last, the upper and insole on the upper being lasted. The outer sole, laid between these gages, and in the clamps to be described, will, when the jaws are moved 90 in, be brought by the gages to its proper position for being tacked or nailed to the laps of the upper and to the insole.

Within each set of the jaws m n o is another set of jaws, p' q r, which are provided with 95 clamps s, to extend from them, as represented. Fig. 6 is a nearly horizontal section taken length-wise of the jaws m, n, and o and their auxiliary jaws p', q, and r, from which it will be seen that each of the jaws p', q, and r is supported 100 by a stop-slide, s', and against one or more spiral springs, t, supported by and extending

into a screw, *u*, screwed into the next adjacent outer jaw. This screw serves to vary the pressure of the spring against the jaw as circumstances may require. The springs *t* are placed 5 against the stop-slides *s'*, and also other springs *t* may be arranged to bear against the auxiliary jaws at other points, as shown, giving these jaws a firm but yielding pressure.

Each clamp *s* has the shape shown, so as to 10 fit over the upper and hold it firmly in place, and such clamp may be provided with a small gravitating toothed pawl, *v*, (see Figs. 7, 8, and 9,) the first of such figures being a top view, the second a bottom view, and the third 15 a longitudinal section, of the clamp and its pawl. The pawl is arranged within and projects down through the clamp, and is pivoted to it. As the jaw carrying the clamp moves inward the pawl catches the leather of the upper and aids the clamp in forcing it forward, the clamp subsequently extending over and holding the lap of the upper down upon the insole. On the jaw receding from the leather 20 the pawl will readily pass out of it, being carried off with the clamp and jaw.

Held to the ends of arched pieces *H* and an arm extending from post *B* is a slide, *L*, to which is attached an adjustable fork, *K*, adapted for holding the heel of the boot or shoe.

30 To last an upper by the machine, the last, with the upper on it, is to be placed bottom upward upon the tops of the posts *B C*, with the heel part of the upper within the adjusting-fork *K* projecting from the slide *L*, supported 35 by the post. The prongs of the said fork should be adapted to the slide, so as to be adjustable toward or from each other as the size of the shoe may require, and the slide is to be so applied to the post as to be movable toward and 40 away from the other part. On moving the slide toward the opposite post and up to the heel part of the upper the upper and last can be adjusted in position for the jaws to act against the upper. Next, both sets of jaws 45 are to be caused simultaneously to approach the upper and last. In so doing they will

stretch the upper firmly on the last, and the outer jaws will crowd it down upon the insole, the clamps being forced over and upon the laps, so as to hold them firmly down. After 50 tacking down the lap at the toe and heel and paring down the laps, where necessary, at the bends thereof, the attendant is to lay the outer sole between the gages and to force down the pedal, so as to bring the outer sole and insole and last into their correct relative positions. Having done this, he is to drive nails 55 through the outer sole, the laps, and into or through the insole. The shoe thus lasted and prepared is next to be removed from the machine and further treated, as hereinbefore mentioned.

In the said machine I claim as my invention as follows:

1. In a lasting-machine, the combination of 65 the inner sets of jaws and their clamps with the outer sets of jaws and their sole-gages, such inner jaws having stop-slides and being applied to the outer ones, the latter having mechanism for forcing them inward, and the springs 70 for supporting the inner jaws, all being to operate substantially as set forth.

2. In a lasting-machine, the combination of 75 the posts *B C* and the fork *K*, adjustable as described, with the inner and outer sets of jaws, provided with clamps and sole-gages, mechanism for operating the said jaws, the inner jaws having stop-slides, and the springs for supporting such jaws, substantially as set forth.

3. In a lasting-machine, the combination of 80 the toothed pawl *v* with each of the jaw-clamps *s*, such pawl being applied to the clamp in manner and to operate substantially as set forth.

4. In a lasting-machine, the combination of 85 the sliding posts *B C* with the adjustable standards *D* and the rotary cams *E* thereof, arranged with such posts, as set forth.

MARTIN R. ETHRIDGE.
